CURTAIN ROD HOLDER

Filed Sept. 30, 1937

FIG. 1.

FIG. 2.

Inventor

JOHN ZBOCK

By *Adam E. Fisher*

Attorney

UNITED STATES PATENT OFFICE

2,135,159

CURTAIN-ROD HOLDER

John Zbock, Bellaire, Ohio

Application September 30, 1937, Serial No. 166,480

1 Claim. (Cl. 248—262)

My invention relates to improvements in curtain rod holders or brackets and the main object is to provide a device of this kind which may be readily applied to a window frame without mar- 5 ring the same and which will rigidly support the curtain rod across the frame.

Another object is to provide a device of the kind in a simple and inexpensive form made up of a single length of strip material bent and shaped to provide a supporting finger adapted to rest on the upper corner and edge of a window frame and to which it is fastened by pins driven into the frame edge, a downwardly turned arm adapted to fit against the vertical and lateral edge of the window frame, and a forwardly and horizontally extended arm adapted at its end to engage and support the curtain rod, the weight of the rod being transmitted back to the arm alongside the frame which resting against the wall rigidly supports the entire assembly in the de- 20 sired position.

These and more specific objects will be made evident in the course of the following specification, reference being had to the accompanying drawing wherein

Figure 1 is a perspective view showing my invention in use, the window frame and curtain rod being shown fragmentally.

Figure 2 is a perspective view of my invention alone.

Referring now with more particularity to the drawing, Figure 1 thereof shows the upper right corner portion of a window frame A and an end portion of a conventional tubular form of curtain rod B which has an extremity C turned at right angles and adapted to be supported horizontally across the frame A a short distance below the upper edge D of the frame. Hitherto, this has been done by a bracket nailed or screwed directly to the face of the window frame but in this case the entire weight of the curtain and rod is carried by the nails or screws, causing them to loosen and require frequent replacement. This also mars the appearance of the frame and it soon becomes very unsightly.

My invention provides a holder or bracket 5 made up from a single long strip of metal or other suitable material bent at right angles to its length at 6 to form a mounting arm 7 and bracing arm 8 extended at right angles and adapted thereby to fit over the upper corner portion of the frame A, as shown in Figure 1. In this position the arm 7 overlies the upper edge D of the frame and it may be secured thereto by means of pins or prongs 9 which are secured at 10 to the arm and in use are driven into the frame. These pins 9 might also take the form of pointed teeth punched out of the arm itself. The

bracing arm 8 then drops down over the vertical edge E of the frame with one edge extending along and in engagement with the wall F.

A rod supporting arm 11 is then formed by bending the strip along a diagonal line 12 at the lower extremity of the arm 8 so that this arm 11 extends vertically on edge in a forwardly and horizontally extended plane from the frame A. The extremity of the arm 11 is turned back on itself at 13 forming a tongue 14 which terminates in a 10 narrow lip 15 extended at right angles.

In use the device is mounted as shown and described and the curtain rod B has its end C slipped over the tongue 14 up against the lip 15 whereupon the resiliency of this tongue will maintain a 15 frictional engagement with the rod to hold it in place.

The weight of the curtain rod and the curtain (not shown) thereon is supported rigidly by the arm 11 since it transmits the weight back 20 to the arm 8 which, bearing back against the wall F, sustains the arm 11 and the weight of the curtain as will be understood. The arm 11 cannot itself bend under the weight since it stands edgewise to the strain. In this manner 25 the weight is actually supported against the wall and the pins 9 serve only to hold the device in place on the frame and consequently they will not readily become loosened. In any event the mounting is entirely on the edge of the frame 30 and the face thereof cannot be marred.

The brackets are of course made in pairs for use on both the right and left sides of the window, the only difference in construction being the direction in which the various bends are made.

While I have herein set forth a certain preferred embodiment of my invention, it is understood that I may vary from the same in minor details, so as best to provide a practical device for the purposes intended, not departing from the 40 spirit of the invention and within the scope of the appended claim.

I claim:

A curtain rod bracket for mounting over the upper corner of a window frame projecting inwardly from the wall surface, the said bracket comprising an integral strip including a mounting arm adapted for flatly overlying the upper edge of the window frame, a bracing arm adapted to extend downwardly and flatly overlie the outer 45 lateral edge of the frame, a horizontally extended rod supporting arm, and a backwardly turned spring tongue at the extremity of the rod supporting arm, the said tongue being adapted for resiliency and frictionally engaging the inturned 50 tubular end of a curtain rod.

JOHN ZBOCK.
